UNITED STATES PATENT OFFICE.

JOHN DRYSDALE NASMITH, OF TORONTO, ONTARIO, CANADA.

BAKING-OVEN.

No. 846,046.

Specification of Letters Patent.

Patented March 5, 1907.

Application filed December 17, 1903. Serial No. 185,582.

To all whom it may concern:

Be it known that I, JOHN DRYSDALE NASMITH, of the city of Toronto, in the county of York, in the Province of Ontario, Canada, 5 baker, have invented certain new and useful Improvements in Baking-Ovens, of which the following is the specification.

My invention relates to improvements in baking-ovens, and particularly to the class 10 known as the "reel-type" oven; and the object of the invention is to produce a compact oven for baking, of a comparatively light weight, minimum size, and convenient form, which will possess a maximum baking- 15 surface, occupying but little floor-space, in which the products may be handled expeditiously, in which the amount of heat and moisture in the oven may be regulated to a nicety, in which the radiation from the machine or oven will be reduced to a minimum, 20 and practically all waste heat carried off; and it consists, essentially, of an oven comprising a casing substantially cylindrical in form and having heat-non-conducting walls, 25 suitable standards for supporting the same, an interior drum, a reel secured on the shaft, which extends through the center of the drum and eccentrically to the casing, a series of baking-plates pivotally connected to the 30 reel, a hood, moisture-supplying means, a feed and discharge door and shelf, a receiving-table, an endless conveyer, and driving means, all arranged and constructed in detail as hereinafter more particularly 35 explained.

Figure 1 is a perspective view of my improved baking-oven, portion of the hood and heat-non-conducting material being broken away to exhibit the construction of the cylindrical portion. Fig. 3 is a longitudinal section. Fig. 2 is a cross-section. Fig. 4 is a detail view.

In the drawings like letters of reference indicate corresponding parts in each figure. 40 A is the cylindrical casing, which is supported on the standards or pedestals B at each side by means of the brackets C C, which extend through the side walls a a of the casing and are secured thereto by the 45 inner plates c c, which are secured to the brackets by the bolts c' c' or by any other suitable means.

D is a shaft which extends eccentrically 50 through the casing for a reason which will hereinafter appear, such shaft being jour-

naled in suitable roller-bearings D' D' located on the brackets C.

d are packing-rings surrounding the shaft D at the inside of the roller-bearings D'.

The casing A is made with a heat-non-conducting covering on the side walls, as well as on the peripheral wall, such covering being formed in sections A' on the sides, which are suitably fitted in between retaining-ribs a'. The heat-non-conducting covering may 60 be made of asbestos, mica, or any other suitable heat-non-conducting material. The peripheral wall of the casing is also formed in sections with retaining-ribs a'', between which the heat-non-conducting material is fitted 65 and held. It will thus be seen that the baking-chamber will effectually retain the heat, thereby increasing its control, saving fuel, and avoiding discomfort in the workshop, as well as lessening risks from fire by 70 overheating adjacent structures. 75

E is a hood of substantially the form of the upper portion of the cylinder and having a flue E' centrally disposed, to which is connected an extension-flue to carry off the heat 80 and steam. The hood is slightly larger than the cylinder and flares at the bottom. The hood is provided with the sides e of a form concentric to the shaft, and whereby such hood is secured to the ends of the cylinder. 85

F is a drum secured to the shaft D and closed at both ends, and f are radial arms secured to the drum and connected together at the outer end by the links f'.

f'' are baking plates or trays, which are 90 pivoted on the rods f''' on the ends of the arms, such pins extending through the ends f'''' of the trays, formed as shown or in any other suitable form.

f'' are rollers secured to one end of the plates 95 or trays so as to engage with the arm M, hereinafter described.

G is a worm-wheel secured on the shaft D and meshing with the worm g on the spindle G', which is supported on suitable journal-brackets g', secured to the pedestal or standard B.

H and H' are tight and loose pulleys on the end of the shaft G'.

h is a bevel-pinion located on the opposite end of the shaft to that on which the pulleys H and H' are situated and meshing with a bevel-pinion h'' on the end of the vertical spindle h'', which is journaled in suitable bearings h''', attached to or forming part of 105 110

the standard B, and is provided with a hand-wheel h^5 . The trays or plates f^2 are caused to rotate ordinarily by means of the worm-wheel G, worm g, and pulleys H and H', driven from a suitable source of power, and assume the position indicated in Fig. 3 in rotating.

I is a tank partially filled with water, which is provided with any suitable means 10 to prevent its overflowing, such as a ball-tap, (not shown,) and I' is a trapped pipe leading therefrom to a tray i', located centrally in the baking-chamber, as indicated in Fig. 3. The tray i' being at a proper level is supplied 15 with water, which on account of the heat of the oven evaporates into the baking-chamber. The tray i' is such a size as to supply just the proper amount of moisture for the baking. The heat is supplied by means of gas- 20 burners J, located near the bottom of the baking-chamber, as indicated in Fig. 3. Instead of gas-burners any other suitable means for introducing heat into the oven may be utilized; but I preferably utilize gas 25 as the simplest and most convenient.

K is the feed and discharge orifice, which is provided with a closing door or flap K', having handles k and supporting-arms k^2 and k^3 . The arms k^2 and k^3 at each end of 30 the cylinder are pivotally connected to the door and to the casing, the pivot-points on the casing being eccentric to the cylinder or shaft. The arms k^3 are provided with counterbalancing-weights k^4 at their short ends. 35 The pivot-point of the arm k^2 is farther away from the center than the pivot-point of the arm k^3 , and consequently when the door k' is thrown open it passes upwardly from the opening k easily, and, vice versa, 40 when it is thrown down it closes easily onto the opening. The door being balanced will when raised remain open.

L is a shelf, which is supported on inclined ways l at each end and provided with 45 bottom racks l' and engaged by the pinion l^2 on a cross-rod l^3 , which is turned by a hand-wheel or handle l^4 , so as to throw the shelf in and out of the discharge-opening when the door is opened.

M are arms pivoted at their upper ends in the walls of the casing and provided with a notch m at the lower end and a pivotally-slotted connection at m' to the shelf L.

N is a tray having arc-shaped bottom ends 55 n, which are supported on end rollers n' on the truck N', the wheels of which rest on suitable rails n².

O is an endless conveyer located beneath the oven and extending from the trucks N' to a 60 point at or beyond the hood. The conveyer O is provided with cross-slats, but may be of any suitable form.

When it is primarily desired to fill the oven with the products, the door may be 65 swung open and the baker may by turning

the hand-wheel h^5 adjust the trays opposite the lower side of the orifice K and place the products on each tray in succession. When placing the products in the oven, of course the truck N' would be pushed out of the way 70 toward the conveyer O, so that the baker can bring the racks containing the products close to the door for convenience of placing them on the trays.

The oven is in practice brought to the required temperature before any of the articles to be baked are placed on the shelves, the doors being open during the time the oven is being heated. Then the articles or products to be baked are placed on the shelves, and the oven may be rotated by the driving-pulley H, driven by a belt from any suitable source of power. During the baking and in the intervals when the baked articles are not being removed from the shelves the door may be 80 closed; but as it is in practice being opened at short intervals for the removal of baked articles and the insertion of unbaked ones there is plenty of opportunity for the escape 85 of the products of combustion, especially as 90 the door does not fit hermetically. After the goods have been baked sufficiently the power would be thrown off, and the baker after opening the door K' may by turning the handle l^4 adjust the shelf L inwardly, so as 95 to bring the arms M inwardly into the position shown in dotted lines in Fig. 3. By now turning the hand-wheel h^5 the tray to the left of the shelf is brought into the tilted 100 position shown in dotted lines by means of the roller f^5 on the front edge thereof contacting with the notched end of the arm M. The truck N' is of course previously brought 105 into the position shown in the drawing, with the receiving-tray, however, in the position shown in dotted lines. It will thus be seen that the products will slide off from the plates f^2 over the shelf L and onto the receiving-tray N. The truck N' may now be 110 pushed forwardly toward the endless conveyer O and the receiving-tray tilted into the reverse position to that shown in dotted lines, so as to deposit the products upon the endless conveyer O. In this position the receiving-tray and truck will be out of the 115 road. The baker then may by means of the hand-wheel h^5 turn the plates backwardly, so that the empty plates will be close to the lower side of the discharge-opening. The unbaked goods from a new rack may then be 120 placed upon a plate and the shelf L withdrawn by turning the handles l^4 . The fresh goods may be then brought with the plate f^2 in the horizontal position past the shelf L and arms M. After this is done the shelf 125 will be pushed inwardly again, so as to bring the arms into the position shown in dotted lines, and the next succeeding plate will be tilted in the same manner as the preceding one, the other parts having been brought into 130

the receiving position hereinbefore described. It will thus be seen that the products of each shelf in the oven may be discharged and the shelf reloaded immediately thereafter, and 5 thereby a great deal of time saved.

It will be seen from this description that the area to be heated of my baking-chamber is reduced to the smallest possible space by the drum F. It will also be seen that I provide ready means for rotating the baking-plates by power or by hand and also sufficient moisture in the baking-chamber, so essential in some styles of loaf-bread. The casing being mostly covered by a hood, it will also be 10 readily understood that the steam and heat when bread or cakes are being taken out will pass up and out of the building.

Another advantage which I attain in my construction is the accessibility in placing the 20 products in the baking-chamber or removing it therefrom. Besides, I am enabled to save floor-space, as there is no long draw-plates or peel used. It will also be understood that the door being practically at the bottom of 25 the oven the heat and moisture will be retained in the oven to a maximum extent. Again, on account of the construction of my oven I am enabled to make it practically a machine which is readily adaptable for erection 30 on either upper or lower floor, and not only this, but it may be taken apart and re-erected when it is desirable to extend or change the premises.

What I claim as my invention is—

35 1. In a baking-oven of the reel type, a cylindrical casing, suitably supported, and provided with an orifice or mouth for feeding and discharging the products near the bottom of the casing and in the periphery thereof, whereby a maximum amount of heat is 40 preserved in the oven, a door, and means for moving the door eccentrically to the cylindrical portion of the casing containing such door, so as to close the orifice in the periphery 45 of the casing, as specified.

2. In an oven of the reel type, the combination with the casing and feed and discharge orifice, of a door for the same balanced so as to remain in an open or closed position and 50 so arranged that it will move in an arc eccentric to the casing, so as to close and open the orifice, as specified.

3. In an oven of the reel type, the combination with the cylindrical casing having a 55 feed and discharge orifice, and the shaft, of rotatable baking-shelves suitably carried by the shaft, rollers on the ends of each of said baking-shelves adjacent the outer edge thereof, arms provided with notched lower ends, 60 and pivoted at their upper ends, in the interior of the ends of the casing above the orifice therein, and means for throwing such arms inwardly into the path of the shelves, as specified.

4. In an oven of the reel type, the combi-

nation with the cylindrical casing having a 65 feed and discharge orifice, and the shaft, of rotatable baking-shelves suitably carried by the shaft, arms pivoted at their upper ends in the interior of the ends of the casing above the orifice therein, and moving parallel with 70 the end walls, a cross-plate pivotally connected to the lower ends of the arms, and means for throwing the plate inwardly, as specified.

5. In an oven of the reel type, the combination with the cylindrical casing having a 75 feed and discharge orifice and the shaft, of rotatable baking-shelves suitably carried by the shaft, arms pivoted at their upper ends in the interior of the ends of the casing, a 80 plate pivotally connected to the lower ends of the arms, racks formed at the bottom of the plate and pinions suitably operated and meshing with such racks, as specified.

6. In an oven of the reel type, the combination with the cylindrical casing having a discharge-orifice and the shaft, of baking-shelves suitably carried by the shaft, a movable plate extending from the lower side of the orifice at an inclination outwardly, and a 90 tilttable receiving-tray located beneath the plate and so pivoted that when tilted the planes of the tray and plate are coincident as specified.

7. In an oven of the reel type, the combination with the cylindrical casing having a discharge-orifice and the shaft, of baking-shelves suitably carried by the shaft, a movable plate extending from the lower side of the orifice at an inclination outwardly, a tilt- 100 able receiving-tray located beneath the plate and provided with arc-shaped ends, rollers journaled in suitable bearings on which the arc-shaped ends are supported, and a supporting-truck for the tray, as specified. 105

8. In an oven of the reel type, a cylindrical casing forming the baking-chamber and provided with an orifice in the periphery thereof near the bottom and which the front portion of the casing of the oven overhangs, means 110 for supporting the casing above the floor, so as to leave a clear space underneath the oven, whereby the baked products discharged from the orifice may be removed rearwardly underneath the oven away from the unbaked products brought to the orifice to refill the shelves, and a hood enveloping the whole upper surface down to the level of the orifice and spaced from the casing to form a flue to carry away 115 the steam of the baked products, and gases 120 from the whole oven, as specified.

9. In an oven of the reel type, a cylindrical casing forming the baking-chamber and provided with an orifice in the periphery thereof near the bottom and which the portion of the 125 casing of the oven at the front overhangs, means for supporting the casing above the floor, so as to leave a clear space underneath

the oven, a receiving means for the baked products in proximity to the orifice and a supplemental receiving means located in a space underneath the oven to carry the baked products to the rear of the oven clear of the unbaked products brought to the oven-mouth to refill the shelves, and a hood enveloping the whole upper surface down to the level of the opening and spaced from the casing to form a flue to carry away the steam of the baked products, and gases from the whole oven, as specified.

10. In an oven of the reel type, a cylindrical casing forming the baking-chamber and 15 provided with orifice in the periphery thereof near the bottom and which the portion of the casing of the oven at the front overhangs, means for supporting the casing above the floor, so as to leave a clear space underneath 20 the oven, a tilttable receiving-tray designed to be thrown to incline downwardly and outwardly to receive the products from the oven and have its inclination reversed to discharge the products of the oven underneath the casing and an endless belt designed to receive 25 such baked products and carry them to the rear of the oven clear of the unbaked products brought to refill the shelves and a hood enveloping the whole upper surface down to 30 the level of the opening and spaced from the casing to form a flue to carry away the steam

of the baked products, and gases from the whole oven, as specified.

11. In an oven of the reel type, a cylindrical casing forming the baking-chamber and 35 having an opening near the bottom and a hood enveloping its whole upper surface down to the opening, spaced from the casing, and provided with front and rear bottom openings, and an exit-flue at the top of the 40 hood to carry off the steam of the baked products, and gases from the whole oven, as specified.

12. In an oven of the reel type, the combination with the cylindrical casing forming a 45 baking-chamber, of ribs forming a frame for supporting the casing at the inside and forming pockets at the outside, and the heat-non-conducting material secured in and filling the pockets between the ribs so as to entirely 50 cover the interior casing as specified.

13. In an oven of the reel type, a cylindrical casing provided with end walls, standards or pedestals, and brackets supported on top of the standards or pedestals, and interior 55 plates secured to the inside of the walls, and bolts securing such plates to the brackets extending through the walls, as specified.
